W. Beck Jr.

ATTORNEY.

UNITED STATES PATENT OFFICE

HARDING O. JORDAN, OF LANGSTON, OKLAHOMA

CIGARETTE CASE

Application filed December 13, 1928. Serial No. 325,852.

The present invention relates to cigarette cases and has for an important object to provide a casing having a cigarette container slidably mounted therein and normally disposed inwardly of the casing and adapted for movement outwardly thereof whereby to expose the cigarettes for convenient removal from the container.

A further important object is to provide a casing open at its forward side and arranging a spring actuated door upon the container for swinging into open position upon a predetermined outward movement of the container from the casing.

15 A still further object is to provide an article of this character of a simple and practical construction, which is neat and attractive in appearance, relatively inexpensive to manufacture and otherwise well adapted for the 20 purposes for which the same is intended.

Other objects and advantages reside in the special construction, combination and arrangement of the various elements forming the invention, as more fully hereinafter 25 described and claimed, reference being had to the accompanying drawings forming part hereof, wherein like numerals refer to like parts throughout the specification and in which

30 Figure 1 is a front elevational view of the device in open position,

Figure 2 is a side elevational view thereof with the open position of the container shown in dotted lines,

35 Figure 3 is a front elevational view of the device in closed position, and

Figure 4 is a transverse sectional view taken along a line 4—4 of Figure 3.

Referring now to the drawing in detail, 40 wherein for the purpose of illustration I have disclosed a preferred embodiment of my invention, the numeral 5 designates a casing of rectangular formation having its front and bottom side open and provided 45 along the top portion of its front side with a substantially narrow apron 6 which depends downwardly from the top of the casing. A vertically extending slotted opening 7 is formed in the back 8 of the casing having its bottom portion enlarged as shown at 9. Ver-

tically slotted openings 10 are also formed in each of the side walls 11 of the casing and likewise are enlarged at their bottom ends as shown at 12. A cigarette container 13 of a shape similar to the casing is slidably mounted within the casing and is open at its top. The upper portion of the front wall 14 of the container is formed into a door 15 hingedly connected along its lower edge in any suitable manner well known in the art as shown at 16 and provided adjacent each side of the hinge with a wire spring 17 for normally urging the door outwardly and downwardly into open position as more clearly illustrated in Figure 1 of the drawing.

A pair of trunnions 18 extend outwardly from the opposite sides of the container for vertical sliding movement in the openings 10, each of the trunnions having heads 19 preventing withdrawal of the trunnions from the openings. A headed stud 20 also extends outwardly from the rear wall of the container and arranged for vertical sliding movement in the opening 7, the enlarged portion 9 of said opening being suitable for permitting withdrawal of the head of the stud through the opening when the container is disposed in its lowermost position, as more clearly illustrated by the dotted lines in Figure 2 of the drawing. Such removal of the stud 20 permits the rearward swinging movement of the lower end of the container so as to bring the top of the container forwardly for convenient withdrawal of the cigarettes therefrom.

The inner face of the apron 6 is formed with a shallow recess 21 for receiving a lug 22 formed on the outer face of the door adjacent its upper edge whereby to normally retain the container inwardly of the casing. The lower portion of the front wall of the container is provided with a recessed finger grip 23 by means of which the container may be moved downwardly in the casing for releasing the door. The forward edges of the side walls 11 of the casing are provided with a pair of inwardly extending lugs 24 adapted to engage the opposite side edges of the door during the initial outward movement of the container, said door being provided at its opposite side edges with notches 25 through 100

which the lugs 24 are adapted to pass upon a predetermined outward movement of the container whereby to permit the springs 17 to swing the door into open position.

5 It will be apparent from the foregoing that the cigarette case constructed in accordance with my invention is of a novel construction and neat design and may be manufactured in any suitable material such as 10 light weight metal and ornamented in an attractive manner.

It is obvious that the invention is susceptible of various changes and modifications without departing from the spirit thereof or 15 the scope of the appended claims, and I accordingly claim as my own all such forms of the invention to which I am entitled.

I claim:

1. A cigarette case of the class described 20 comprising a casing open at its front and bottom sides, a cigarette container mounted for sliding movement in the casing and open at its upper portion, trunnions carried by the container and supported by the casing for 25 the pivotal movement of the former when arranged in outward position and a door hingedly mounted at the front side of the container.

2. A cigarette case of the class described 30 comprising a casing open at its front and bottom sides, a cigarette container mounted for sliding movement in the casing and open at its upper portion, trunnions carried by the container and supported by the casing for 35 the pivotal movement of the former when arranged in outward position, a door hingedly mounted at the front side of the container, spring means yieldably urging the door in open position and means carried by the casing engageable with the door for retaining the same in closed position when the container is disposed within the casing and during a predetermined outward movement thereof.

3. A cigarette case of the class described 45 comprising a casing open at its front and bottom portions having vertically extended slotted openings in its rear and side walls, each of said openings being enlarged at the lower end thereof, a cigarette container slidably mounted within the casing, a pair of trunnions extending outwardly from the opposite sides thereof and slidably disposed in the openings in the sides of the casing, a headed stud extending outwardly from the 50 rear wall of the container and slidably disposed in the opening of the rear of the casing with the head of the stud adapted for normally retaining the upper end of the container within the casing and adapted for 55 withdrawal through the enlarged lower end of the opening, said container having its upper portion open, a door hingedly mounted along its lower edge and forming the front wall of the container at the upper portion 60 of the opening, said container having its upper portion open, a door hingedly mounted along its lower edge and forming the front wall of the container at the upper portion 65 thereof, spring means yieldably urging the

door outwardly, said door having a pair of notches formed at its opposite side edges, interengaging means between the upper edge of the door and the top of the casing for releasably securing the container inwardly of the casing and lugs formed at the opposite sides of the casing and engageably with the door for normally retaining the same in closed position and adapted for releasing the door upon the movement of the container 75 into a position for registering the notches with said lugs.

In testimony whereof I affix my signature.
HARDING O. JORDAN.
